HEATING APPARATUS

Edwin Fitch Northrup, Princeton, N. J., assignor
to Ajax Electrothermic Corporation, Ajax Park,
N. J., a corporation of New Jersey

Application September 24, 1930, Serial No. 484,121

19 Claims. (Cl. 219—13)

My invention relates to the inductive heating of metallic sheets or plates.

One purpose of my invention is to inductively heat a resistor muffle having a secondary current path passing about more than one muffle chamber.

A further purpose is to heat interior walls of a resistor muffle by induced current conducted from the point of induction through the interior walls.

10 A further purpose is to induce electric current in the outside walls of a muffle and to pass the current through the partition walls between compartments in the muffle.

15 A further purpose is to provide a tortuous or serpentine secondary current path whose convolutions include a plurality of muffle compartments within which heating is effected.

20 A further purpose is to interrupt the edge of an induction furnace resistor secondary in order to require that the induced current travel through a longer path to utilize the additional heating effect secured.

A further purpose is to provide parallel compartments having walls forming a heating resistor for the compartments, and to induce current in the compartment walls, spacing parts of the separating walls to cause the current to travel on both sides of the spacing in order 30 to heat the entire wall.

A further purpose is to longitudinally slit a partition wall between two parallel compartments which are to be heated electrically so that electric current induced in the walls of the compartments may be caused to traverse a path about the slit, increasing the resistance while avoiding increase in the secondary reactance.

35 A further purpose is to utilize not only the sides but the end of a muffle as an electrical resistor in which heat is generated through induction of electric current.

A further purpose is to interrupt the continuity of the end of a resistor muffle in which current is induced so that the end of the muffle 45 may be heated by passage on both sides of the interruption.

40 A further purpose is to inductively heat a plurality of electrical resistors forming a muffle compartment, one resistor being axially above another, and desirably to change the number of resistors used according to the dimensions of the charge.

45 A further purpose is to make up a multiple compartment muffle from separate resistor sec-

tions, each including part of all of the muffle walls.

A further purpose is to vertically insert a plurality of charges concurrently within a plurality of parallel chambers in a muffle.

60

A further purpose is to use a common closure for the charge-inserting ends of a plurality of parallel muffle chambers.

A further purpose is to bell a plurality of muffle compartments so as to retain gases lighter than air within the compartments and to insert the gas preferably after the charge has been applied.

55 Further purposes will appear in the specification and in the claims.

70

My invention relates to the processes involved as well as to apparatus by which the processes can be carried out.

I have preferred to illustrate one main form only with modifications, selecting a form which is practical, efficient and highly advantageous but which has been selected primarily because it illustrates to the best advantage the principles involved.

75

Figure 1 is a broken transverse section partly in elevation, showing the parts of one form of my construction ready for operating assemblage by insertion of the charges.

80

Figure 2 is a broken top plan view of one resistor section used in Figure 1.

85

Figure 3 is a broken section of Figure 2 taken upon line 3—3.

90

Figures 4, 4a and 4b are broken top plan views corresponding to Figure 2 but showing modifications.

95

Figure 5 is a fragmentary section upon line 5—5 in Figure 4, slightly modified by omission of the dowel, and having added a view of the next muffle section with electrical insulation between the sections.

100

Figure 6 is a broken bottom plan view of the muffle end section shown in Figure 1.

105

Figure 7 is a broken section taken upon line 7—7 of Figure 6.

110

In the drawings similar numerals indicate like parts.

At the present time considerable difficulty is encountered in the heating of metal sheets and plates preliminary to annealing. Hundreds of tons of such sheets are treated daily which are not more than one-sixteenth of an inch thick and some of which are as large as eight feet long and four feet wide. If the charges be overheated the material will be ruined, while underheating will not permit satisfactory anneal-

115

ing. Unequal heating is likely to cause buckling of the plates.

At the present time the heating of steel sheets for use in automobile bodies requires about 18 hours in one typical installation.

My invention is excellently suited to heating sheets of this character quickly and uniformly; but adaptation of the invention to meet the exacting requirements of this particular work does not mean that the invention is unsuited to other heating applications.

Aside from annealing there are not only numerous other purposes for which relatively broad and thin metal must be heated, as, for example, preliminary to stamping and forming operations, but other objects require heating for the same and for other purposes.

I have discovered that induced current may be applied to great advantage for such heating of not only flat sheets and plates but such deformed sheets or plates nested or individually and also to the heating of objects of regular or irregular contours.

The heating of sheets and plates is, however, so far the best illustration known to me and is so likely to be one of the main uses to which my invention will be applied that I therefore have shown apparatus primarily designed for this purpose. Wherever I refer to my charge as a "sheet" it will be understood, however, that any suitable shape of charge is included within this designation, the muffle compartments merely being made to conform to the dimensional requirements of the particular product to be heated.

By my invention I inductively apply current to a resistor comprising the muffle walls. As the depth of penetration of the flux is relatively short, and as good coupling is required, substantially all of the induced current will be developed in the periphery of the resistor.

I have therefore provided artificial means for conducting the induced current from the peripheral point at which it is developed into the parts of the muffle which are not directly accessible to the induction. For this purpose I provide an electrically conducting path for diverting the induced current into the interior of the muffle, particularly into the partition walls between individual muffle chambers.

Aside from the resistance heating of the interior parts of the muffle, the elongated current path through these interior parts has certain advantages not at first apparent. In the first place, this path increases the resistance of the secondary circuit, thus causing a certain amount of RI^2 heating in the elongated path.

Furthermore, the maximum power will be absorbed by a secondary when the secondary resistance equals the secondary reactance. Since in my partition walls the current on opposite sides of the walls is flowing in opposite direction, the path through the partition walls is substantially non-inductive and does not tend to increase the secondary reactance. It will however increase the secondary resistance, and as the reactance is ordinarily more than the resistance, will improve the power consumption.

I find it convenient to build up my muffle of a plurality of inductively heated resistors placed one upon another. Since, when these are properly registered, adjacent parts of adjacent resistors will be at the same potential, no insulation need be placed between resistor sections.

When the dimensions of the charge sheets are

varied from time to time I will similarly add or remove muffle sections to or from my muffle without the necessity of making new muffle sections. Of course, if the charge dimensions be increased in two directions beyond the maximum chamber dimension of the muffle section, I will then be obliged to employ new muffle sections.

Since in many cases the charge will suffer from oxidation, I will ordinarily employ a protecting or treating atmosphere in my muffle to avoid injury to the charge.

Describing the structure of Figure 1 in illustration and not in limitation.

I have shown a multiple compartment muffle 10 made up of sections 11 between which no difference of potential is intended to exist and which are therefore rested one upon another, being quickly and easily aligned by means of dowels and openings 12, 12'.

The muffle is shown as bottom-loading at 13 and for this reason is rested upon a platform 14 having an opening 15. About the muffle and upon the platform I place an inductor coil 16 supplied with current from any suitable source 17. Conventional power factor correction is shown by condensers 18. At the top the muffle is closed by a cover 19.

Electrical insulation for the coil is shown at 20. This at the same time acts as a retaining wall, if such be needed, for a finely divided 105 heat insulator 21 which may be poured into the space and over the combination muffle. Because of the use of slits or cuts in the muffle cover, afterwards discussed at length, I use strips 22 to prevent the finely divided material from passing into the compartments 23, 24 and 25 of the muffle. The various parts of Figure 1 are conventionally divided at the middle by broken lines 26 to indicate that the number of compartments may be increased if desired.

The finely divided material used may be any suitable heat insulator of which zircon sand is a good example, but of which diatomaceous earth—on sale under the name of silocel—is the best example known to me.

It is desirable though not necessary to use a heat insulating top above the finely divided refractory, which top I show at 27. This is independently supported and is provided with covered openings 28 through which the refractory may be sifted.

Where metal sheets 29 of steel or iron for example are to be heated they are preferably baled and tied at 30 and are rested upon their edges on a bottom closure 31 which ultimately fits into the opening 15 in the platform, sealing the opening. This closure is effected by lifting the bottom 31 by means of plungers 32 of hydraulic elevator cylinders 33 which are shown as having inlet and outlet fluid supply and discharge connections 34 and 35, of which obviously the set 34 would be sufficient with some types of hydraulic plunger.

The elevator plungers act through a transverse platform 36 which in the lowered position 140 of the platform rests upon the floor 37 of a car 38 whose wheels 39 travel to and from the observer on a track 40. The track is supported by beams 41 through ties 42.

For the purpose of injecting a special atmosphere into the muffle, whether to protect against oxidation, treat the charge, or otherwise, I show a connection 43. Where the atmosphere is lighter than air, the muffle interior will act as a gas bell.

Whether the muffle is made up in a single section or is of unit construction as seen in Figure 1, my invention provides for heating not only the outside of the muffle, but also the interior partitions of the muffle by current induced directly in the outer muffle walls and conducted through the partition. I secure this highly desirable effect in practice by interrupting the passage of current through the outer walls at the partitions 10 and directing this current in series through one side of each partition, toward the opposite outer wall, and back through the other side of each partition, the induced current then continuing through the outer wall.

15 The detail of how this diversion of the current path is secured is not important to the broader aspects of my invention, which contemplates the artificial extension of the current path to pass through the partition walls in series with the outer walls. The most convenient way of carrying out the invention is to form a partition divided through most of its length parallel to one of its surface planes and electrically connected at the ends with the adjoining outer walls, so 25 that the entire partition is in series with the outer wall.

In Figure 2 there is shown one of the resistor sections such as are illustrated in Figure 1. This may be cast integrally whether the divisions 30 are cast in or cut in.

The muffle chambers are separated by partition walls 44 and 45. Each of the walls 44 and 45 is separated interiorly at 46 or 47, dividing the partition wall 44 into two conductors 48 and 35 49 and likewise dividing the partition wall 45 into two conductors 50 and 51.

Remembering that the inductor coil surrounds the outer surface of the resistor, current will be induced for example in the outside conductor 52 40 and likewise in the short end conductor 53 and will tend to flow around the outside of the resistor. Due, however, to the separation 46, the secondary current will be compelled to flow through the conductor 48, then across at 54 45 and finally back through the conductor 49 on the other side of the partition wall.

This current and more current there induced 50 will then flow through the end conductor 55, but will be again diverted by the separation 47 of the partition wall 45, and will take the path through the partition conductor 50, across at 56 and back through the opposite partition conductor 51 to the end conductor 57. The secondary circuit will then be completed through the 55 outside conductors 58 and 59.

It will be evident that the form of the resistor may be varied in a number of ways immaterial to my invention. I have illustrated a number of these variations in Figures 4, 4a and 4b.

60 In Figure 4 the separations 46 and 47 bear the same relation to the other structure as in Figure 2, but the partition wall has been separated at 60 and 61 from the end wall 59. Electrically I consider this change of relatively 65 little importance because it does not vitally alter the current path in the partition, which in any case will be through the partition conductors 48 and 49 or 50 and 51.

In Figure 4a I illustrate the partition separations 46 and 47' extending from opposite ends 70 of the outside muffle wall. I also show a separation between the outside wall 59' and the partition wall at 60, but no corresponding separation at the opposite end of the other partition wall. It will thus be seen that the separations

60 and 61 at the ends of the partition walls are optional.

In Figure 4b I illustrate longitudinal partition separations 46² and 46³ performing the function of the partition separation 46, and extending from opposite ends toward the interior to the area 54', where the separations cease. In this case the induced current will travel in from both sides of the outer wall through the partition wall, across at 54' and back through the opposite partition wall.

The separations 47² and 47³ are similar to 46² and 46³, and are discontinued at 56' to permit the current to flow from one side of the partition wall to the opposite side of the partition wall.

In Figure 5 I illustrate fragments of two resistor sections 11 placed one above another and separated by electrical insulation 62. In this figure I have omitted the dowel for insuring that the adjoining sections register. The insulation will then insure that points of different potential do not come into contact.

Figures 6 and 7 illustrate an end section for the muffle. For convenience the end section is domed at 63 to provide additional interior capacity for the muffle. Separations 46⁴ and 47⁴ correspond generally with the partition separations in the interior sections. In addition the centers of the domes contain longitudinal separations 64 to insure that current will flow through the tops of the domes to heat them.

It will be evident that the relation between the resistance and reactance in the secondary circuit will be affected by the frequency, which 110 must therefore be considered to determine the difference between the reactance and resistance when this difference is sought to be made up. The frequency selected will, of course, make a difference in the depth of penetration, requiring thicker walls for lower frequency, the walls being preferably not less in thickness than three times the depth of penetration and certainly not less than twice the depth of penetration. It must be remembered also that with higher frequency the heating effect is improved at temperatures above the decalescence point with iron or steel and for all temperatures with non-magnetic metals.

The most desirable metal for most purposes is 125 cast iron. Whether this is to be considered as a magnetic or non-magnetic material for frequency purposes will, of course, depend upon the purpose for which the muffle is used and the temperature to which it is to be raised.

It will be evident that by my invention I take 130 advantage of the induction of current in the outside walls of the muffle close to the inductor coil to build up an appreciable flow of current and I then conduct the current thus inductively produced into interior walls of the muffle where I use it advantageously to heat parts in which it would not be possible directly to induce current.

I believe that I am the first thus to divert 135 current induced in the walls of a resistor muffle to be used for resistance heating elsewhere.

I believe also that I am the first to assemble 140 an inductively heated muffle comprising a plurality of chambers from a series of units built up one against another.

It will be evident that I have provided not only an adjustable muffle of unusual adaptability and convenience both in manufacture and in use but that I have made accessible for 145

- direct induction the interior of the structures which hitherto have been inaccessible and which have relied for their heat upon conduction from the exterior surface.
5. It will be evident that there is a considerable advantage in coupling in having the primary coil conform to the shape of the secondary and in spacing it uniformly from the secondary.
- In view of my invention and disclosure variations and modifications to meet individual whim or particular need will doubtless become evident to others skilled in the art, to obtain all or part of the benefits of my invention without copying the structure shown, and I, therefore, claim all 15 such in so far as they fall within the reasonable spirit and scope of my invention.
- Having thus described my invention, what I claim as new and desire to secure by Letters Patent is:
20. 1. An inductor, a source of current connected thereto and a secondary therefor of electrically conducting but high resistance material within the inductor having partition walls carrying current in series with current induced in the outer walls.
2. A resistor forming walls of a muffle adapted to be used with a surrounding primary coil and having interior partition walls electrically in series with its outside walls.
30. 3. A secondary muffle resistor adapted to be used with a surrounding inductor coil and having the resistance of its outside walls increased by artificially lengthening the circuit path within the interior of the muffle.
35. 4. A muffle secondary resistor adapted to be used with a surrounding inductor primary and having the length of its secondary current both artificially and non-inductively increased at a distance from its outer walls.
40. 5. A secondary muffle resistor adapted to be used with a surrounding inductor coil and having the resistance of its outside walls artificially increased by including in series within their circuit partition walls, the increase being non-inductive and sufficient to make the resistance of the circuit approach the value of the reactance so that the power consumption is increased.
50. 6. In a multiple secondary resistor having a plurality of compartments, outer electrically conducting compartment walls, and electrically conducting interior partition walls divided in the planes of the walls, each division being cut through an outer wall.
55. 7. A resistor muffle secondary adapted to be used with a surrounding inductor primary and having interruptions in the surface of the resistor across the induced current path, providing an artificially extended length of secondary conductor path returning upon itself about the interruption.
60. 8. A muffle having a plurality of compartments and a serpentine electrically conducting wall therefor, in combination with an inductor coil surrounding the entire wall and inducing current through the convolutions of the serpentine wall.
65. 9. A resistor muffle secondary for use with a surrounding inductor primary and having outer side and end walls and partitions between opposite walls to divide the muffle into compartments and having the walls from which the partitions spring and the partitions separated for a considerable distance toward the opposite walls through the lengths of the partitions, whereby current induced along the outer walls in a direction generally across the partitions will follow one partition part at the separation to a point of juncture of the separated parts and back again to the same outer wall and will continue through the outer wall to the next separation.
80. 10. A resistor muffle secondary adapted to be used with a surrounding inductor primary made up of separate sections divided parallel to the current paths and each apertured perpendicular to the division to form in the aggregate compartments of adjustable height depending upon the number of sections used.
85. 11. A multiple compartment resistor muffle secondary of adjustable height having parallel compartments and comprising independent resistor sections divided transversely across the compartments.
90. 12. A resistor muffle secondary section having a plurality of openings transversely to the plane of the section corresponding with compartments to be built up from the sections and having the partition walls between the openings divided in the planes of the partition walls from side to side of the section parallel with the longer dimension of the openings and from one terminal wall about the opening nearly to the opposite wall.
95. 13. A plurality of muffle secondary sections, each having a plurality of openings transversely to the plane of the section corresponding with compartments to be built up from the sections and having the interior partition walls between the openings divided in the planes of the partition walls from side to side of the section parallel with the longer dimension of the openings and from one terminal wall about the opening nearly to the opposite wall and means for ensuring that parts of one section do not engage parts of another section which have a different potential.
100. 14. A resistor muffle end secondary adapted to close a plurality of muffle compartments and to receive induced current from a primary surrounding the muffle, having the walls of the muffle end separated inwardly from outside edge walls at intervals a substantial distance toward an opposite edge in order that current induced about the perimeter of the muffle end will follow the line of the separation to a juncture point and back again to the same edge of the muffle.
115. 15. A multiple compartment resistor muffle secondary of adjustable height having parallel compartments and comprising independent resistor sections divided transversely across the compartments open at the bottom in combination with means for inserting charges from beneath, and a closure for the bottom upon which the charges rest.
120. 16. A multiple compartment resistor muffle secondary of adjustable height having parallel compartments and comprising independent resistor sections divided transversely across the compartments open at the bottom in combination with means for inserting charges from beneath, a closure for the bottom upon which the charges rest, a closure for the top of the muffle and means for inserting a special atmosphere within the muffle as a bell.
135. 17. A resistor muffle secondary of non-circular cross section and a non-circular inductor primary closely surrounding it and conforming generally to the shape of the secondary.
140. 18. A resistor muffle secondary adapted for use with a surrounding inductor primary, having a plurality of compartments with interior par-

titions between them separated through to the outer walls to artificially extend the path of the induced current so that the resistance of the induced current at the frequency selected will 5 approach the reactance of the circuit.

19. A resistor muffle secondary adapted for use with a surrounding inductor primary, having a plurality of compartments with interior

partitions between them separated through to the outer walls to artificially extend the path of the induced current and in which the thickness of the outer and partition walls traversed by the secondary circuit is at least twice the 80 depth of penetration of the induced current at the frequency chosen.
